UNITED STATES PATENT OFFICE.

MORRIS H. ELVIDGE, OF NEW YORK, N. Y.

ROOFING MATERIAL.

1,414,778.

Specification of Letters Patent. Patented May 2, 1922.

Application filed January 3, 1922. Serial No. 526,674.

To all whom it may concern:

Be it known that I, MORRIS HARRISON ELVIDGE, a citizen of the United States, residing at the city of New York, borough of 5 Manhattan, county and State of New York, have invented a certain new and useful Roofing Material, of which the following is a specification.

This invention pertains to roofing material, more particularly, to flexible roofing material wherein a surface layer of granulated material is incorporated with an underlying layer composed usually of a bituminous substance, commonly referred to 15 in this art as asphaltum.

Roofing of the character under consideration as universally made and used is characterized by a sameness or uniformity of color which presents an optical effect quite 20 displeasing because of the monotonous coloring and the absence of an artistic appearance, the granular material of the roofing usually presenting a single color scheme, such as an all red, green, gray, or a so-called 25 "blue black" color appearance.

Various attempts have been made to relieve the monotonous appearance of roofing to the eye, such as by so-called "shadow effects," or by an assemblage of different colored shingles (such as red and green) in alternate order or otherwise; but all such prior constructions and modes of use have not satisfactorily met the requirements because lacking in the artistic effect.

35 In the present invention the purpose has been to produce roofing material which in and of itself and independently of the mode of laying presents a pleasing and artistic color scheme in the appearance of the 40 weather surface to the eye of an observer.

To this end, differently colored granular materials are incorporated with the bituminous layer of the roofing material so as to result in distinguishable areas of different colors in the weather surface formed by granular material, some of which areas are of one color, other areas of a different color, and still other areas are characterized by a mixture of the different colors which blend or 45 shade into the areas of contrasting colors, the whole producing a multi-colored weather surface presenting a more or less ununiform, or as it may be termed, a streaky color scheme of an artistic and pleasing 50 character.

In the drawings—

Figure 1 is a plan view of shingles embodying this invention as they appear when laid to form a roofing.

Figure 2 is a sectional view of the shingle, and

Figure 3 is an enlarged view illustrating the blending or shading of one area into other areas of contrasting colors as embodied in my invention.

As is usual in the art pertaining to composite roofing materials, I employ a base A composed generally of an absorbent felt material. This base is saturated or impregnated in one way or another with a water

resistant agent, such as asphaltum of a low melting point and adapted to be maintained by heat in a liquid condition, whereby the felt material may be run with a continuous motion within a bath of said liquid asphaltum so as to become saturated therewith. Subsequent to the saturation of the absorbent felt material with the liquid asphaltum, the saturated material is coated, upon one or both surfaces thereof, with a layer B

composed usually of asphaltum the melting point of which is considerably higher than that of the asphaltum employed in waterproofing the absorbent felt. This superficial coating B of the character specified is

employed in layer form upon one or both surfaces of the saturated felt to afford protection to the latter against the heat of the sun's rays and the deteriorating influence of the weather, such coatings when applied to the top and under surfaces of the saturated felt serving the function of a "seal," so-called, for precluding the exudation, to a material extent, of the water resistant agent incorporated with the absorbent felt.

The weather surface of the roofing material is constituted by a layer C of granular material, all of which, or substantially all of which, is in the same plane, in contradistinction to the so-called "shadow effect" obtained in part by resorting to elevations and depressions in the weather surface.

According to my improvement, the weather surface is characterized by a multi-color appearance presenting an artistic optical effect, and this is obtained by single-color areas c, d, usually of contrasting colors, and other areas e which shade into or blend with such contrasting color areas, said shaded or

blended areas *e* being composed of a mixture of differently colored granular materials which harmonize with the colored areas *c*, *d*. The granular materials ordinarily used for color effect in different roofings are red, green, and the so-called "blue black." In my roofing material, the differently colored granular materials are so incorporated with layer B as to obtain well defined areas of contrasting colors, such as granular material of a red color in areas *c*, granular material of a green or "blue black" color in areas *d*, and a blend or mixture of two colors (such as red and green) of granular materials in the areas *e*, the composite color obtained by the mixture of granular material in areas *e* blending with or shading into the contrasting colors of the granular material in the areas *c*, *d*, the ensemble of such colors presenting to the eye a pleasing color effect on the weather surface of the roofing. The areas *c*, *d*, *e*, are well defined and distinctly appear in the weather surface so as to be readily observable and distinguishable, but the extent of the individual areas is not a constant factor but varies according to the desired design. Thus, there is a well defined area of a red color, as *c*, another readily distinguishable area, or areas, *d* composed of green or "blue black" granular material, and third areas, as *e*, not so perceptible to the eye but nevertheless present in the weather surface and presenting a composite color obtained by a mixture (either uniform or variable) of the red and green (or "blue black" instead of green) granular materials, such areas *e* of composite color shading into the single areas *c*, *d*, of contrasting colors, with a view to presenting a streaky or variegated appearance somewhat analogous to the appearance obtained by nature in the effect of a sunset in the sky when more or less obscured by clouds.

In the production of roofing with a weather surface composed of granular material, it is customary to deposit such granular material of a single selected color within a hopper, and to feed such single color granular material in a thin stream continuously upon a hot adhesive layer B of asphaltum, whereby the granular material adheres to the tacky layer and, under pressure, becomes incorporated therewith so as to be embedded therein, more or less, thus presenting a one color surface extending continuously over the asphaltum layer so as to protect the latter from deterioration due to the action of the weather. Subsequent to the deposit of the granular material upon the asphaltum layer present upon the felt base, the web of roofing is conducted usually around drums acting to apply pressure to the granular material for embedding the same as described, as well as to provide for the discharge, by gravity, of the excess granular material from

the surface of the roofing material and to expose the resulting composite roofing material to the cooling effect of the atmosphere. Such composite roofing material may be used in sheet or strip form, or it may be severed by suitable cutting mechanism to produce individual shingles of suitable dimensions.

In making my improved roofing material, granular materials of more than one color are used, and to this end there is deposited in, or supplied to, the distributing hopper granular materials composed of a plurality of selected colors. Accordingly, I supply to the hopper at one time granular material of a red color, other granular material of a green or "blue black" color, and another quantity of granular materials composed in part of a red color and in part of green or "blue black" color. Such batches of differently colored granular materials are supplied by the hopper and in a thin continuous stream to the tacky surface formed by the layer B upon the felt material A, so as to become incorporated with the layer B, and there is thus formed a multi-colored weather surface composed in part of well defined areas *c* of granular material of one color, other well defined areas *d* of granular material of a different color contrasting with the first mentioned areas, and still other areas *e* of a composite color blending or shading into the two contrasted color areas mentioned. As will be apparent, the granular materials composed of different contrasting colors, and composed, also, of a mixture of colors, are fed to the sheet material at one and the same time from the same (or different) hoppers, as a result of which the weather surface is composed of differently colored granular materials the areas of which are variable in extent, although readily distinguishable by the eye, and the surface is thus multi-colored and shaded or blended to attain a variegated appearance, rather than a monotonous single color effect.

As stated, the composite roofing may be used in sheet form, or in strip form, but it is preferable to cut the sheet material into individual units or shingles of desired dimensions. Such shingles are adapted to be laid by workmen in the usual manner, without any attempt to assort or group the same according to selected color; but, on the contrary, the shingles or units, with multi-colored weather surfaces or with blended or shaded surfaces supplementing such multi-colored surfaces, are laid or installed indiscriminately and without selecting the same for the color effect, notwithstanding which absence of care or skill in selection, my roofing presents a variegated color effect.

It is apparent that the granular materials used may be of a desired character, such as slate, crushed stone either artificial or natural, or other flaky or comminuted material

suitable for the purpose. The granular material is in small particles, either uniform or ununiform as to dimensions and size, but ordinarily such granular material is uniform 5 as to size so as to pass through a screen of certain dimensions.

It will be observed by reference to Figure 3 of the drawing that the parallel areas of contrasting colors are each greater in extent 10 in longitudinal than in transverse direction and irregular in outline where one joins the other and that there is a distinct area of composite color into which the contrasting areas shade. This results in attractive distinctive features with the colored areas in sharp contrast with one another. And by 15 reference to Figure 1 it will be observed that when this material is applied to a roof, say in the form of shingles, the areas of contrasting and composite colors produce a diversified variegated surface of contrasting and composite colors with the colored areas of the several units in non-uniform or broken up relation to one another, so that diversity 20 instead of sameness of appearance is given to the whole surface and a softer and more pleasing effect given with also clearness and life in the contrasts produced. It also makes possible giving to different roofs 25 covered with the same material different effects by the indiscriminate placing of the individual units so that no two roofs will be exactly alike.

It will be understood that quantities of 30 differently colored granular materials are to be supplied by the feed mechanism so as

to flow in a definite stream of selected contrasting colors; but the granular material of a composite color is formed by a mixture (either uniform or varied) of the differently 40 colored granular materials, in equal or unequal proportions, or, if desired, such composite color granular material is supplied by the simultaneous feed and admixture of the selected contrasting colored materials. 45

Having thus fully described the invention, what I claim as new and desire to secure by Letters Patent is:

1. A roofing material having a granular material weather surface characterized by 50 distinct parallel areas of contrasting colors and distinct areas of composite color into which the other areas shade, the areas being greater in extent in longitudinal than in transverse direction. 55

2. A roofing material having a granular material weather surface characterized by distinct parallel areas of contrasting colors and distinct areas of composite color into which the contrasting areas merge, the various areas having irregular outline where one merges into the other, the roofing material being subdivided into individual units to produce in the indiscriminate assemblage of the units a diversified variegated surface 60 of contrasting and composite colors, with the individual units differing one from the other in color relationship. 65

In testimony whereof I have hereto signed my name this 31st day of December, 1921. 70

MORRIS H. ELVIDGE.
